LASTING MACHINE

Corwin W. Baker, Beverly, Mass., assignor to
United Shoe Machinery Corporation, Flemington, N. J., a corporation of New Jersey

Application January 2, 1948, Serial No. 228

12 Claims. (Cl. 12—8.3)

1

This invention relates to machines for lasting shoes and particularly to a novel machine for lasting progressively along the edge of the bottom of a shoe. In one aspect, this invention constitutes an improvement on the machine disclosed in United States Letters Patent No. 2,326,193, issued on August 10, 1943, in the name of the present applicant.

In the machine of the aforementioned patent, the lasting margin of the stock to be lasted is tensioned, heightwise of the shoe, and the shoe is fed along, by means of a pair of inclined rolls which engage the lasting margin and exert a frictional drag thereon. As the lasting margin of the tensioned stock leaves these rolls, it is wiped inwardly from the edge of, and pressed against, the shoe bottom by means of a rotary wiper. During the operation of this machine, the lasting margin of the stock is gripped firmly between the two rolls, one of which directly engages the adhesive coated inside surface of the lasting margin. Because of the firm grip of the rolls on the lasting margin, when operating on shoes having rather sharply curved bottoms, e. g., steep shanks, it not only is difficult for the operator to tip the shoe, in a lengthwise direction, in order to maintain it in proper operative position, relatively to the rolls; but also such lengthwise tipping of the shoe may result in wrinkling of the upper materials along the side of the shoe. In addition, the rotating roll which is in direct engagement with the inside surface of the lasting margin may tend to wipe off, or otherwise disturb, the adhesive coating thereon.

It is an object of this invention to provide a novel and improved lasting machine in the use of which the aforementioned difficulties are avoided. To this end, the herein illustrated lasting machine has novel tensioning means comprising a driven roll and a cooperating gripping element, for yieldingly holding the lasting margin of the stock against the driven roll and movable with the stock when pull is exerted thereon, together with means for periodically separating said gripping element and the driven roll so as to cause the driven roll to exert an intermittent frictional pull on the stock. In common with the machine of the above-mentioned patent, the herein illustrated machine is provided with a wiper for wiping the lasting margin of the tensioned stock inwardly from the edge of, and for pressing it against, the shoe bottom. More particularly, the driven roll may be mounted for rotation on an axis disposed at an angle to the bottom of a shoe and, having an operating sur-

2

face for engaging the outer side of the lasting margin, and the cooperating gripping element a finger which has an operating surface for engaging the inner side of the lasting margin and is pivotally mounted for movement with the stock, against the action of a spring which returns it to its original position, when the finger and the rolls are separated.

Inasmuch as the lasting margin of the stock is fully released, each time the roll and finger are separated, the shoe may be readily tipped, in a lengthwise direction, without any danger of wrinkling the stock on the side of the shoe. Also, the finger, which is drawn along by the lasting margin of the stock, as it is tensioned by the roll, has no tendency to rub off, or otherwise disturb the adhesive coating on the inside surface of the lasting margin of the stock. In addition to tensioning the stock, the intermittent frictional pull applied to the lasting margin, by means of the inclined roll, also effects a feeding movement of the shoe and, as the shoe is thus fed along, the lasting margin of the tensioned stock is wiped inwardly from the edge of, and pressed firmly against, the bottom of the shoe by means of the wiper, herein illustrated as a driven chain.

The above and other objects and features of the invention will become apparent from the following detailed description of the preferred embodiment thereof, illustrated in the accompanying drawings, and will be pointed out in the claims.

In the drawings,

Fig. 1 is a view in side elevation of the machine embodying the features of this invention;

Fig. 2 is a view in front elevation of the machine shown in Fig. 1;

Fig. 3 is a plan view of the machine shown in Fig. 1; and

Figs. 4 and 5 are views showing the operating elements only of the machine, that of Fig. 4 being a view from a plane indicated by the line IV—IV, Fig. 3, looking in the direction of the arrows, while that of Fig. 5 is a sectional view substantially on the line V—V, Fig. 3, looking in the direction of the arrows.

Referring to the drawings, the operating instrumentalities of the machine therein illustrated comprise a driven roll 10 and a cooperating pressure element or finger 12, for tensioning the stock to be lasted and for feeding the shoe, together with a driven chain 14, for wiping the lasting margin of the tensioned stock inwardly from the edge of, and against, the shoe bottom. During the operation of the aforementioned in-

strumentalities, the shoe being lasted is positioned, in a heightwise direction, by the engagement of the wiping chain and a shoe bottom rest 16 with the bottom of the shoe, and in a widthwise direction by means of an edge gage 18. As will be apparent from Figs. 3 and 4, when the shoe is positioned in the manner just explained, the axis of the roll 10 will intersect the shoe bottom at an angle, while the marginal edge of the shoe bottom will be substantially in line with the operating surfaces of the roll 10 and pressure finger 12. Accordingly, and as will be explained in more detail below, the lasting margin of the stock will be pressed against the roll 10 by the finger 12 and will be subjected to a frictional drag, imposed by the roll, tending to tension the stock and also to feed the shoe. When the lasting margin of the tensioned stock passes beyond the roll and pressure finger it is immediately wiped inwardly from the edge of, and pressed firmly against, the bottom of the shoe by the wiping chain 14.

The roll 10 is fixed to the end of a shaft 20 which is journaled in an elongated bearing 22 that is secured, by means of screws 24, to an upstanding portion 26 of a bracket 28, Figs. 1 and 3. This bracket is adjustably supported on a base plate 30 by means of an arcuate key 32, which engages an arcuate groove 34, formed in the bracket, and screws 36 that pass through arcuate slots 38. The center of curvature of the arcuate key 32, groove 34 and slots 38 is located on the outer edge of the roll 10 so that the inclination of this roll, relative to the bottom of a shoe, may be varied without materially changing the position of the roll, heightwise or lengthwise of the shoe bottom. The roll 10 is driven from a pulley 40, secured to the shaft 20, by means of a belt 42 which is connected to a suitable source of power (not shown).

The finger 12 is pivotally supported, by means of a pin 50, in a block 52 which is carried on a stud 54, formed integrally with an arm 56. This arm is pivotally supported, by means of trunnion pins 58, 58, on ears 60, 60 which project outwardly from the upstanding portion 26 of the bracket 28, Figs. 1 and 3. A compression spring 62, interposed between a boss 64, formed on this arm, and a hand nut 66, threaded onto a stud 68 that is fixed in the bracket 28, tends to swing the arm in a clockwise direction, see Fig. 1, and to urge the finger 12, yieldingly, toward the roll 10. Actual contact between the finger 12 and the roll 10, however, is prevented by means of an adjustable stop screw 70, carried by the bearing 22. For separating the finger 12 and roll 10, to facilitate the introduction of the lasting margin of the stock to be lasted therebetween, a treadle-operated rod 71 is secured to the arm 56.

The roll 10 is tapered, see Fig. 1, and its operating face is preferably roughened, as by knurling, to increase its frictional grip on the stock being lasted. The finger 12 is provided with an operating surface 72, which is a portion of a cone, complementary to the operating surface of the tapered roll 10 and having its generating axis common with the axis of the pin 50, see Figs. 1 and 2. The finger 12 is normally held in the position in which it is shown in Fig. 2 by means of a leaf spring 74. However, as will be presently explained, this finger is movable with the roll 10 during the operation of the roll to tension the stock and to feed the shoe. Fig. 5 shows this finger, in solid lines, in a position in which it has been moved by the roll 10, and, in dotted lines, in

a position to which it has been moved by the spring 74.

The shoe-bottom rest 16 is adjustably mounted in the lower end of an L-shaped bracket 80 which is secured to the top of a boss 82, Fig. 1, formed integrally with the bearing 22, by means of screws 84, see Fig. 3.

The wiping chain 14 is trained over a pair of idle sprockets 90, 90, Fig. 2, and a driving sprocket 92, Fig. 3. These sprockets are supported on the opposite ends of an elongated bar 94 which is adjustably secured to an angle bracket 96 by means of screws 98 and slots 99. The bracket 96 is likewise adjustably supported on a bracket 100, which is mounted on the base plate 30 by screws 102, by means of an arcuate key 104, which engages an arcuate groove 106 in the bracket, and screws 108 which pass through arcuate slots 110. The center of curvature of the key 104, groove 106, and slots 110 is on an axis extending lengthwise of the bar 94 and intersecting the chain 14 substantially in line with the lowermost sprocket 90. Thus, the operating end of the wiping chain 14 may be angularly adjusted, relatively to the edge of the bottom of a shoe being lasted, see Fig. 5, without altering the position of the chain lengthwise of the shoe or with respect to the roll 10 and finger 12.

The edge gage roll 18 is rotatably mounted on the lower end of a rod 112 which is fixed in a block 114. This block is adjustably secured to a bracket 116, by means of a slot 118 and a screw 120. The bracket 116 is adjustably supported on the top edge of the bracket 96 by means of a slot 122 and screws 124, Fig. 3. Thus the edge gage roll 18 may be positioned lengthwise and widthwise of the shoe so as to locate the marginal edge of the shoe substantially in line with the operating faces of the roll 10 and finger 12, see Figs. 4 and 5.

40 The chain 14 is driven, in the direction of the arrow, Fig. 5, in the following manner. The sprocket 92 is secured to a shaft 130, journaled in bearings in the bar 94 and in a bracket 132 formed integrally therewith. This shaft is connected, by means of universal joints 134, 136 and an extensible shaft 138 to a shaft 140 which is journaled in an L-shaped extension 142 of the upstanding portion 26 of the bracket 28. The shaft 140 carries a bevel gear 144 which meshes with a gear 146 that is secured to the shaft 20.

45 For periodically separating the finger 12 and roll 10, the shaft 20 is provided with a cam 150 having two high points 152, 152 which are adapted to engage an idle roll 154, journaled on the stud 54. Thus, the finger 12 will be moved away from the roll 10 twice for each complete revolution of the shaft 20.

50 The operation of the machine which has just been described will now be explained. With the roll 10 and wiping chain 14 operating, the shoe to be lasted is presented to the machine and the lasting margin of the stock to be lasted introduced between the roll 10 and the finger 12. It will be understood that the inside surface of the lasting margin of the stock, and also possibly the margin portion of the shoe bottom, will have been coated with a suitable adhesive. As suggested above, the finger 12 may be separated from the roll 10, by means of a treadle, to facilitate the introduction of the lasting margin. However, after a little practice, the operator can "run" the lasting margin in between the roll and finger without separating these members.

55 Referring now to Figs. 3, 4 and 5, it will be

apparent that the lasting margin of an upper U, shown assembled on a last L together with an insole I, held yieldingly against the roll 10 by the finger 12, will be subjected to a frictional pull in a direction such as to tension the upper, heightwise of the last, and also to feed the shoe. As this frictional pull is continued, and the shoe fed along, the finger 12 will swing, on the pin 50, from the dotted-line position to the full-line position in Fig. 5, so that its operating face 72 follows the stock. Now, as one of the two high points 152, on the cam 150, engages the roll 154, the finger 12 and the roll 10 are separated and the lasting margin of the upper momentarily released. During this interval, the finger 12 will be returned, by the spring 14, to its original position, dotted lines in Fig. 5, so as again to hold the lasting margin yieldingly against the roll when the high point 152 passes beyond the roll 154. This cycle of operations is repeated, twice for each single revolution of the roll 10, so that a rapidly intermittent frictional pull is applied to the lasting margin. As the shoe is fed along, the lasting margin of the tensioned upper is wiped inwardly from the edge of, and pressed against, the bottom of the shoe by means of the wiping chain 14, see Figs. 4 and 5.

Inasmuch as the intervals when the finger is separated from the roll, by the two high points 152 on the cam 150, constitute but a small fraction of the time of a complete revolution of the roll 10, the frictional pull which is applied by the roll, while definitely intermittent in character, is at the same time relatively smooth in its action. However, as the shoe is tipped in a lengthwise direction, to follow the curvature of its bottom, the lasting margin of the upper can readily adjust itself between the roll and finger when these members are separated. Thus the tipping of the shoe, for the aforementioned purposes, is facilitated, and, since the lasting margin can adjust itself between the roll and the finger, no danger of forming wrinkles therein is present. Moreover, inasmuch as the finger 12 moves with the upper, when pull is exerted thereon, by the roll 10, its operating surface 72 maintains contact with substantially the same portion of the inside surface of the lasting margin of the upper, when it is pressing the upper against the roll. Accordingly, there will be little or no tendency for the finger to rub off, or otherwise disturb, the adhesive coating thereon.

Having described the invention, what I claim as new and desire to secure by Letters Patent of the United States is:

1. A lasting machine having, in combination, means for tensioning stock to be lasted, in a direction heightwise of a shoe, comprising a driven roll, a cooperating gripping element for yieldingly holding the lasting margin of the stock against the driven roll, and means for periodically separating said gripping element and said driven roll to cause the driven roll to exert an intermittent frictional pull on the lasting margin, said gripping element being movable with the stock when the pull is being exerted by said roll, and means for wiping the lasting margin of the tensioned stock inwardly from the edge of, and for pressing it against, the bottom of the shoe.

2. A lasting machine having, in combination, means for tensioning the stock to be lasted, in a direction heightwise of a shoe, comprising a

driven roll provided with an operating surface for engaging the outer side of the lasting margin of the stock, a cooperating gripping element having an operating surface for engaging the inner side of the lasting margin and arranged to hold the lasting margin, yieldingly, against the driven roll, and means for periodically separating said gripping element and driven roll to cause the roll to exert an intermittent frictional pull on the lasting margin, said gripping element being movable with the stock when the pull is being exerted by said roll, and means for wiping the lasting margin of the tensioned stock inwardly from the edge of, and for pressing it against, the bottom of the shoe.

3. A lasting machine having, in combination, means for tensioning the stock to be lasted, in a direction heightwise of a shoe, and for feeding the shoe, comprising a driven roll, a cooperating gripping element for yieldingly holding the lasting margin of the stock against the driven roll, and means for periodically separating said gripping element and said driven roll to cause the driven roll to exert an intermittent frictional pull on the lasting margin, said gripping element being movable with the stock when the pull is being exerted by said roll, and means for wiping the lasting margin of the tensioned stock inwardly from the edge of, and for pressing it against, the bottom of the shoe.

4. A lasting machine having, in combination, means for tensioning the stock to be lasted, in a direction heightwise of a shoe, and for feeding the shoe, comprising a driven roll provided with an operating surface for engaging the outer side of the lasting margin of the stock, a cooperating gripping element having an operating surface for engaging the inner side of the lasting margin and arranged to hold the lasting margin, yieldingly, against the driven roll, and means for periodically separating said gripping element and driven roll to cause the roll to exert an intermittent frictional pull on the lasting margin, said gripping element being movable with the stock when the pull is being exerted by said roll, and means for wiping the lasting margin of the tensioned stock inwardly from the edge of, and for pressing it against, the bottom of the shoe.

5. A lasting machine having, in combination, means for tensioning stock to be lasted, in a direction heightwise of a shoe, comprising a driven roll, a finger for yieldingly pressing the lasting margin of the stock against the roll, and means for periodically separating the finger and roll to cause the roll to exert an intermittent frictional pull on the lasting margin, said finger being pivotally mounted for movement with the stock when the pull is being exerted by the roll, and means for wiping the lasting margin of the tensioned stock inwardly from the edge of, and for pressing it against the bottom of the shoe.

6. A lasting machine having, in combination, means for tensioning stock to be lasted, in a direction heightwise of a shoe, comprising a driven roll provided with an operating surface for engaging the outer side of the lasting margin of the stock, a finger having an operating surface for engaging the inner side of the lasting margin and arranged to hold the lasting margin, yieldingly, against the roll, and means for periodically separating the finger and roll to cause the roll to exert an intermittent frictional pull on the lasting margin, said finger being pivotally mounted for movement with the stock when the pull is being exerted by the roll, and

means for wiping the lasting margin of the tensioned stock inwardly from the edge of, and for pressing it against, the bottom of the shoe.

7. A lasting machine having, in combination, means for tensioning the stock to be lasted, in a direction heightwise of a shoe, and for feeding the shoe, comprising a driven roll, a finger for yieldingly pressing the lasting margin of the stock against the roll, and means for periodically separating the finger and roll to cause the roll to exert an intermittent frictional pull on the lasting margin, said finger being pivotally mounted for movement with the stock when the pull is being exerted by the roll, and means for wiping the lasting margin of the tensioned stock inwardly from the edge of, and for pressing it against the bottom of the shoe.

8. A lasting machine having, in combination, means for tensioning the stock to be lasted, in a direction heightwise of a shoe, and for feeding the shoe, comprising a driven roll provided with an operating surface for engaging the outer side of the lasting margin of the stock, a finger having an operating surface for engaging the inner side of the lasting margin and arranged to hold the lasting margin, yieldingly, against the roll, and means for periodically separating the finger and roll to cause the roll to exert an intermittent frictional pull on the lasting margin, said finger being pivotally mounted for movement with the stock when the pull is being exerted by the roll, and means for wiping the lasting margin of the tensioned stock inwardly from the edge of, and for pressing it against, the bottom of the shoe.

9. A lasting machine having, in combination, means for tensioning the stock to be lasted, in a direction heightwise of a shoe, and for feeding the shoe, comprising a driven roll mounted for rotation on an axis disposed at an angle to the bottom of the shoe, a cooperating gripping element for yieldingly holding the lasting margin of the stock against the driven roll, and means for periodically separating said gripping element and said driven roll to cause the driven roll to exert an intermittent frictional pull on the lasting margin, said gripping element being movable with the stock when the pull is being exerted by said roll, and means for wiping the lasting margin of the tensioned stock inwardly from the edge of, and for pressing it against, the bottom of the shoe.

10. A lasting machine having, in combination, means for tensioning the stock to be lasted, in a direction heightwise of a shoe, and for feeding the shoe, comprising a driven roll mounted for rotation on an axis disposed at an angle to the bottom of the shoe and provided with an operating surface for engaging the outer side of the lasting margin of the stock, a cooperating grip-

ping element having an operating surface for engaging the inner side of the lasting margin and arranged to hold the lasting margin, yieldingly, against the driven roll, and means for periodically separating said gripping element and driven roll to cause the roll to exert an intermittent frictional pull on the lasting margin, said gripping element being movable with the stock when the pull is being exerted by said roll, and means for wiping the lasting margin of the tensioned stock inwardly from the edge of, and for pressing it against, the bottom of the shoe.

11. A lasting machine having, in combination, means for tensioning stock to be lasted, in a direction heightwise of a shoe, comprising a driven roll mounted for rotation on an axis disposed at an angle to the bottom of the shoe and provided with an operating surface for engaging the outer side of the lasting margin of the stock, a finger having an operating surface for engaging the inner side of the lasting margin and arranged to hold the lasting margin, yieldingly, against the roll, and means for periodically separating the finger and roll to cause the roll to exert an intermittent frictional pull on the lasting margin, said finger being pivotally mounted for movement with the stock when the pull is being exerted by the roll, and means for wiping the lasting margin of the tensioned stock inwardly from the edge of, and for pressing it against, the bottom of the shoe.

12. A lasting machine having, in combination, means for tensioning the stock to be lasted, in a direction heightwise of a shoe, and for feeding the shoe, comprising a driven roll mounted for rotation on an axis disposed at an angle to the bottom of the shoe and provided with an operating surface for engaging the outer side of the lasting margin of the stock, a finger having an operating surface for engaging the inner side of the lasting margin and arranged to hold the lasting margin, yieldingly, against the roll, and means for periodically separating the finger and roll to cause the roll to exert an intermittent frictional pull on the lasting margin, said finger being pivotally mounted for movement with the stock when the pull is being exerted by the roll, and means for wiping the lasting margin of the tensioned stock inwardly from the edge of, and for pressing it against, the bottom of the shoe.
